UNITED STATES PATENT OFFICE.

HENRY H. FEHRENSCHILD, OF WESTWOOD, NEW JERSEY.

THERMOSTATIC DEVICE.

1,218,384.

Specification of Letters Patent.

Patented Mar. 6, 1917.

Application filed April 15, 1916. Serial No. 91,349.

To all whom it may concern:

Be it known that I, HENRY H. FEHRENSCHILD, a citizen of the United States, residing at Westwood, in the county of Bergen and State of New Jersey, have invented certain new and useful Improvements in Thermostatic Devices, of which the following is a specification.

My invention consists in a new and useful improvement in thermostatic devices, more particularly that type ordinarily used in incubators and brooders for operating devices for controlling the heating system used in connection with the apparatus.

The novelty of my invention resides in the unique combination of a number of thermostatic wafers, of the ordinary form used in incubators, so adapted that the action of any one or more of the wafers will operate the thermostatic device embodied in my invention. Experience has proved that the use of a single thermostatic wafer to operate the temperature control device does not furnish sufficient security to guarantee the proper operation at all times and under all conditions. Therefore in order to insure proper operation, it has been found necessary to supply a number of thermostatic wafers in such a way that the operation of any one or more will properly control the device. The specific embodiment of my invention disclosed herein will indicate the manner in which I accomplish this desired result, the parts being so arranged that the operation of any one or more of the wafers used will insure the proper operation of the device.

In the drawings:

Figure 1 is a plan bottom view of the device.

Fig. 2 is a section on line 2—2, of Fig. 1.

In the drawings:

The numeral 1 designates the cross-bar by which the device is held in the place in which it is to operate. Affixed at right angles to the cross-bar 1 is the second cross-bar 2. At the ends of these cross-bars 1 and 2, are provided the pendant arms 3, pivoted to the cross-bars 1 and 2 in the pivot bearings 4. From the lower end of these

arms 3, extend the levers 5, pivoted to the arms 3 in the pivot bearings 6. Affixed to the under side of the cross-bar 1, are two thermostatic wafers 7, of the usual type of wafers used in such devices. To the under side of the cross-bar 2, there are affixed two-thermostatic wafers 7. These four wafers 7 are so placed as to rest upon the levers 5, so that when the wafers 7 are expanded by the increase in temperature the resulting action will operate the levers 5, swinging them in the pivot bearings 6. At the point of juncture of the cross-arms 1 and 2, there is a circular orifice 8, extending through the cross-arms 1 and 2, through which there is disposed an operating rod 9, to the lower end of which is affixed the plate 10 by means of the set-screw 11. This plate 10 is provided with four circular cavities 12 arranged in its upper face so that each cavity 12 is in line with one of the levers 5 when the plate 10 is in operative position. From the ends of the levers 5 adjacent to the plate 10 extend rods 13 provided with downwardly projecting ends 14 adapted to rest in the cavities 12.

The foregoing description clearly indicates the method of operation of this device. Any one of the four wafers 7, being expanded by an increase in temperature, would force its corresponding lever 5 downward and through the rod 13 draw down the plate 10 and the operating rod 9 connected with the temperature control device.

The nature of the construction makes it apparent that the operating rod 9 may be supplied with a number of plates 10 at varying points, in which levers 5 operated by wafers 7 might be placed, so that any number of wafers 7 could be used.

Having described my invention, what I claim is:

1. The combination in a thermostatic device of a single operating rod; a plurality of pivoted levers, each lever having its free end attached to the rod, and a thermostatic wafer applied to each lever.

2. The combination in a thermostatic device of a pair of cross-arms at right angles to one another, each provided at each of its

ends with a pivoted pendant arm; a lever pivoted in the end of each of the pendant arms and provided with a projecting rod; a thermostatic wafer affixed to the under side 5 of each end of each cross arm and above each lever; and an operating rod passing through an orifice in the two cross arms and provided with a plate adapted to re-

ceive the ends of each of the projecting rods from each of the levers. 10

In testimony whereof I affix my signature in presence of a witness.

HENRY H. FEHRENSCHILD.

Witness:

JOHN E. HARING.
